UNITED STATES PATENT OFFICE

160,657

BOOKCASE

Grover C. Phillips, New Bern, N. C.

Application November 14, 1949, Serial No. 6,036

Term of patent 14 years

(Cl. D33—2)

To all whom it may concern:

Be it known that I, Grover C. Phillips, a citizen of the United States, residing at New Bern, in the county of Craven and State of North Carolina, have invented a new, original, and ornamental Design for a Book Case, of which the following is a specification, reference being had to the accompanying drawing, forming part thereof.

I claim:

The ornamental design for a book case, as shown.

GROVER C. PHILLIPS.
